UNITED STATES PATENT OFFICE.

ALFRED NELSON, OF CHICAGO, ILLINOIS.

FLOOR-SCRAPER.

1,268,873.

Specification of Letters Patent. Patented June 11, 1918.

Application filed January 15, 1917. Serial No. 142,418.

To all whom it may concern:

Be it known that I, ALFRED NELSON, a citizen of the United States, and resident of Chicago, in the county of Cook and State of Illinois, have invented certain new and useful Improvements in Floor - Scrapers, of which the following is a specification.

The common method now in use for scraping or finishing floors consists in doing the work by hand scrapers, the workmen getting down on the floor in order to do the scraping. This is a very slow process, besides being exceedingly hard work. The present invention relates to a machine for doing this work, which can be operated by the workmen standing in an upright position, and by means of which better and more efficient work may be done.

The objects of the present invention are to provide an improved machine for scraping floors; to provide a machine of this character which may be operated by one or two men; to provide a floor scraping machine which will operate while moving in either direction; and in general, to provide such an improved structure as will be more fully described hereinafter.

In the accompanying drawings illustrating this invention:

Figure 1 is a side view;

Fig. 2 is a bottom plan view;

Fig. 3 is a longitudinal sectional view;

Fig. 4 is an end view, with parts broken away to show the interior construction.

In the particular form of my invention shown herein, I provide a carriage comprising a frame or body portion 5, mounted on axles 6 and 7 provided with wheels 8 and 9. One or more scrapers may be used, but

I prefer to provide a scraper at each end of the carriage, one of these scrapers being brought into operation when the carriage is moving in one direction, and the other scraper being operated when the carriage is moved in the opposite direction. The scraper 10 is mounted on an oscillating shaft 11, carried in bearings 12 at one end of the frame, and the scraper 13 is carried on an oscillating shaft 14, mounted in bearings 15

at the opposite end of the frame. The shafts 11 and 14 are provided respectively with upwardly extending arms 16 and 17, which are

pivotedly connected at their upper ends to a pipe or tube 18, which extends longitudinally of the machine. It will be noted that 55 when the tube 18 is moved longitudinally, it will rock the shafts so as to bring one or the other of the scrapers into engagement with the floor or surface to be acted upon, and I provide means for connecting this 60 tube with the handles, so that the proper scraper will be brought into engagement when the machine is being moved in the proper direction for it to act. For instance, the left-hand scraper, shown in Fig. 1, is 65 the one which will be in operation when the machine is moving to the right, and the right-hand scraper will be acting when the machine is moving to the left. In order to do this and also provide two handles, so that 70 the machine can be operated by two men, I arrange a rotatable shaft 19 at approximately the center of the machine, this shaft having an upwardly extending arm 20, which passes in through a slot 21 in the tube 75 18, and engages with slides or plungers 22 and 23 in the tube. A compression spring 24 is inserted between the plunger 22 and an adjustable abutment 25, which is adjusted by means of a set screw 26 passing through the 80 threaded end of the tube 18. A corresponding spring 27 is inserted between the plunger 23 and an adjustable abutment 28, which is adjusted by means of a screw 29 passing through the opposite end of the tube 18. The 85 shaft 19 is also provided at either end thereof and within the side of the frame, with downwardly extending forked arms 30, for the handles or tongues 31 and 32. The handle 31 is provided with a fork 33, which is 90 pivotally connected to the left-hand branches of the arms 30, and the handle 32 is provided with a fork 34, which is connected to the right-hand branches of the arms 30. In order to readily attach and detach the handles, pivots 35 are carried on the ends of springs 36, which are secured at their opposite ends to the corresponding forks 33 and 34, the arrangement being such that by 95 pressing the springs inwardly or toward the center of the machine, the pivots will be withdrawn from the ends of the arms 30, thereby permitting the handles to be removed or placed in position. 100

The yielding connections provided between the tongues or handles and the scrapers may be adjusted to give any desired pressure on the scrapers, but it may be desired in some cases to positively limit the swinging movement. The end of the shaft 19 is therefore connected with an arm 37, which extends upwardly on the outside of the frame, between two lugs 38 and 39. 5 These lugs are provided respectively with set screws 40 and 41, which may be adjusted to limit the swinging movement of the arm 37.

In order to lock the machine so that 15 neither scraper is in operative position when it is being drawn by the handles, a locking bar or lever 42 is pivoted at 43 to a lug on the frame, and is adapted to engage with a slot 44 in the outwardly extending end of 20 the shaft 19. This handle is held in raised or locking position by means of clamping members 45, with which it engages closely when in raised position.

With the machine in position on a floor or 25 surface to be scraped, and the shaft 19 being unlocked to permit its oscillation, one operator, for instance, pulls on the handle 32, which will oscillate the shaft 19 and will swing the arm 20 to the left, thereby moving 30 the tube 18 to the left and swinging the scraper 10 down against the surface, and this scraper will remain in operative position as long as the machine is being pulled by the handle 32. If the other workman simultaneously pushes on the handle 31, the 35 action will be substantially the same. When the machine has reached the end of the surface which is being scraped, it is then moved in the opposite direction by the operator 40 pulling on the handle 31, which in turn will swing the arm 20 to the right and bring the scraper or tool 13 into engagement with the surface. The scrapers or tools for acting on the surface may be made of any suitable 45 material and of any form desired, but, as an illustrative example, these scraping tools may be made of sharpened steel blades, approximately six inches in length. These blades will require sharpening and adjustment, and are so arranged that this may be 50 readily done. For instance, each blade 46 is held in a holder comprising plates 47 and 48. The plate 47 is rigidly secured to the corresponding oscillating shaft, and has two pins 49 adjacent to the ends thereof. The plate 48 is cut away at the corners, so as to 55 fit in between these pins. A screw 50 passes through the plate 48 and through a slot 51 in the blade 46, and is threaded to engage 60 with a threaded hole in the plate 47. The blade 46 may be readily removed by loosening the screw 50, and when the blade is inserted, it may be clamped in position by

tightening this screw. It will be noted that the carriage and operating parts may be 65 readily changed in form and details of construction without departing from the scope of this invention, and therefore I do not wish to limit myself to the exact construction or arrangement herein shown and described, 70 except as pointed out in the following claims, in which I claim:

1. In a floor scraper, the combination of a frame, wheels on which said frame is mounted, adapted to hold the frame in substantially fixed horizontal position with respect to the floor, scrapers pivotally mounted at each end of the frame, connecting means between said scrapers, whereby they will be oscillated in unison to cause one or the other 80 scraper to engage with the floor, handles at each end of the frame for drawing the same pivotally connected with said connecting means and adapted to swing freely up and down, the handles being attached so that 85 when either handle is pulled, it will cause the respective scraper at the opposite end of the machine to engage the floor.

2. In a machine of the character set forth, the combination of a movable frame, a 90 scraper pivotally mounted on said frame, a handle for moving said frame, means for mounting the handle so that it will be longitudinally movable with respect to the frame, and resilient connecting means between the 95 handle and scraper adapted to swing the scraper into engagement with the surface to be acted upon by the longitudinal movement of the handle when the handle is actuated for moving the machine.

3. In a floor scraper, the combination of a carriage, a scraper mounted at each end of said carriage, a handle, means for connecting the handle to the carriage to permit longitudinal movement of the handle and connections between said scrapers and the handle, and arranged so that when one scraper is 105 thrown into engagement with the floor, the other scraper will be thrown out of engagement, said scrapers being actuated by the 110 longitudinal movement of the handle but not by its vertical movement.

4. In a machine for scraping floors, the combination of a body, wheels and axles for supporting said body, cross shafts pivotally 115 mounted at each end of said body, scrapers mounted on said shafts, arms extending upwardly from said shafts, a tube pivotally connected to the upper ends of said arms, a shaft pivotally mounted adjacent to the center of the body, an arm extending from said shaft and engaging with a slot in said tube, adjustable springs between the upper end 120 of said arm and the ends of said tube, arms projecting downwardly from said last-named shaft, and handles connected with 125

said last-named arms and extending outwardly at each end of the body, for operating said machine.

5. In a scraping machine, the combination of a carriage having four wheels, a pair of scrapers pivotally mounted in said carriage, means for connecting said scrapers, whereby one will be thrown out of operative position

when the other is thrown into operative position, a handle, a yielding adjustable connection between the handle and the scrapers, whereby the pressure of the scrapers may be regulated, and means for limiting the movement of the scrapers toward or away from the surface to be acted upon.

ALFRED NELSON.
